FILTERING UNIT FOR A SWIMMING POOL

Norbert L. Reiner, Wallingford, Conn., Donald Huffman, Montreal, Canada, and Joseph Diemond, Simsbury, Conn., assignors to Coleco Industries, Inc., Hartford, Conn.

Filed Oct. 22, 1970, Ser. No. 25,603

Term of patent 14 years

Int. Cl. D23—01

U.S. Cl. D23—4

FIG. 1

FIG. 2

FIG. 3

FIG. 4

FIG. 5

FIG. 6

FIG. 1 is a rear elevational view of a filtering unit for a swimming pool showing the new design;

FIG. 2 is a side elevational view thereof;

FIG. 3 is a bottom plan view thereof;

FIG. 4 is a front elevational view thereof;

FIG. 5 is an elevational view of the opposite side; and,
FIG. 6 is a top plan view thereof.

The conventional electrical cord has been fragmentarily shown in FIGS. 1, 3 and 5 and omitted from FIGS. 2, 4 and 6 for convenience of illustration.

We claim:

An ornamental design for a filtering unit for a swimming pool, as shown.
